TABLE PLANING MACHINE

Eugen Capaul, Zurich, Switzerland

Application November 22, 1949, Serial No. 128,809

4 Claims. (Cl. 90—53)

1
This invention relates to certain improvements in table planing machines.

It is the object of the present invention to increase the efficiency of table planing machines.

A special object of the invention is to provide means permitting a two-stroke operation of table planing machines.

Another object of the invention is to provide means for the adjustment of the faces of the cutters of the cutting devices thereof.

Other and further objects, features and advantages of the invention will be pointed out hereinafter and appear in the appended claims forming part of the application.

In the accompanying drawings a now preferred embodiment of the invention is shown by way of illustration and not by way of limitation.

In the drawings:

Fig. 1 is a central section of a cutting unit for table planing machines having the invention applied thereto.

Fig. 2 is a side view thereof showing the stop mechanism.

Fig. 3 is a front view of the apparatus, with the lateral attachments thereof shown in a section on line III—III of Fig. 1.

Fig. 4 is a perspective view of a table planing machine having the device according to the present invention attached thereto.

Similar reference numerals denote similar parts in the different views.

Referring now to the drawings in greater detail, it will be seen that my novel cutting aggregate comprises five main functional groups, all being somehow connected with the main casing 29, viz:

Group A.—Cutting device

Group B.—Stop device

Group C.—Change-over switch

Group D.—Reversing stops arranged outside of the cutting device

Group E.—Cutter fixing device

These five groups will be hereinafter described individually as follows:

Group A.—Cutting device

The cutting device is accommodated in the main casing 29 and comprises two iron cores 3 and 4 cooperating with solenoid coils 1 and 2 arranged thereabove, two shock absorbing springs 15 and 16 provided above the iron cores 3 and 4, on mushroom-shaped holders 33, 34 which are fixedly mounted in the casing 29 by means which are not shown, a toothed transmission wheel 5 meshing with toothed rack portions 32 and 33 at

the lower ends of the cores 3 and 4, a cutter shaft 11, and a toothed wheel 6 keyed to said cutter shaft and meshing with said transmission wheel 5. The cast iron casing 29 is carried by a base plate 52 and for accurate adjustment of the height of the cutting tool 34 is slidably guided on a further plate 60 above the table 54. The plate 60 is swivel-mounted on a carriage 53 in such a way that it can be swung about a horizontal axis, from its initial or normal position as shown, by 90° in one or the other direction. A cross bar 55 mounted for vertical sliding in the two pillars 56 forms a guide for the carriage 53 lengthwise of which it is slidable in a horizontal direction. On both sides of the casing 29 protrude the two shaft ends of a cutter shaft 11. Mounted on one side of shaft 11 is the cutter 34, Fig. 3, and on the other side an adjustable stop device therefor, shown at B in Figs. 2 and 3. Both ends of shaft 11 being equal, the cutter 34 and the stop device B are interchangeable. The specially designed ends of cutter shaft 11 moreover permit mounting of the cutters in any desired position. Conical collars 45, 46 and conical clamping caps 47 and 48 tightened by screws 49 and 50 serve to fixedly secure the cutter and the stop device on their respective shaft ends. The shaft 11 is mounted in casing 29 so as to be free from vibrations. The workpiece is shown at 51.

Group B.—Stop device

The stop device comprises a base plate 35 mounted on a machined lateral surface provided on either side of casing 29 and accurately fixed by set pins or screws 36. Mounted on the base plate 35 are rotary stop discs 17 and 18 seated on pivots 39 and 40, and worms 20 and 21. Each worm is fixedly mounted on a shaft (not shown) whose end protruding over the plate 35 is adapted for engagement thereover of a spanner. A stop pawl 19 is secured on the cutter shaft 11 after the fixing of the base plate 35 on the casing 29. The stop pawl 19 has two stop faces provided with hardened, interchangeable steel plates 37, 38. The stop discs 17 and 18 have in their lower half a segment-shaped passage opening each (1/16 in) in which are rotatably seated the stop pins 22 and 23 (1/8 in) which are also made of hardened steel and inwardly conically tapered, with a milled stop face. At the periphery of the upper halves of the rotary discs 17 and 18 there are arranged worm wheel segments 24 and 25 in mesh with the worms 20 and 21, respectively, mounted tangentially thereto, for accurate adjustment of the cutting edges of the cutters 34.

Each of the three fixing screws 41 is screwed by its lower threaded end into a lock nut which in turn is engaged in a T-groove in the base plate provided on the same pitch diameter as the screws 41.

Group C.—Change-over switch

The change-over switch 12 is mounted on the front side of the casing 29 and forms the connecting member between the two coils 1 and 2 indicated by dotted lines in Fig. 3 and the two limit switches 13 and 14 which will be herein-after described. Each of the wires 1' and 2' leads to one of the coils 1 and 2. In the normal position I of the pole switch 12 as shown in Fig. 3 the switch 13 is connected to the conductor 1' and the switch 14 is connected to the conductor 2'; in the position II on the contrary the switch 13 is connected to the conductor 2' while the switch 14 is connected to the conductor 1'.

Group D.—Reversing stops

The switches 13 and 14 are fitted on a casing 50 secured to the bed 57 and cooperate with two switch cams 59, 61, the two switches being mechanically interconnected, in the manner as is well known in arrangements comprising such switches for the reversal of the table motion, in such a way that on operation of one of the switches the other switch automatically returns to its position of rest. The cams 59, 61 are operated by two dogs 62 secured to the table 54, only one of these dogs being visible in Fig. 4. In case of movement of the table 54 from the left to the right the stop 62 finally will engage cam 59 and depress the same. Thus, the direction of motion of the table 54 is reversed and simultaneously the switch 13 is operated. In this case, owing to the said coupling between the two switches 13, 14 the other switch 14 together with the cam 61 is moved to its position of rest. When on movement of the table 54 from the right to the left hand side of the second stop 62 not visible in Fig. 4 strikes against the cam 61, the direction of movement of the table 54 is again reversed and simultaneously the switch 14 is operated and the switch 13 released. The switches 13, 14 are parallelly connected, in a manner not shown in the drawing, to a source of current, so that with every operation of one of the switches the coil connected to the respective switch will be excited and remain excited as long as the switch is in its operative position.

Group E.—Cutter fixing device

At the underside of casing 29 is provided a machined T-groove permitting engagement therein of a cutter fixing or adjusting plate 26. By approximately a quarter turn of a threaded bolt 42 screwed into the casing 29, by means of a hand lever 27, a reliable fixing of the plate 26 is achieved which ensures an accurate position of the plate in the vertical axis intersecting with the axis of the horizontal shaft 11. The fixing plate 26 adapted to engage the faces 7 and 8, or 9 and 10, of the cutter 34, will be lined with a hard metal plate 43. In order to prevent damaging of the faces or of the fixing plate by premature operation of the switch 12, a metal strip 44 conforming to the lower projecting part of casing 29 is laterally fastened to the fixing plate 26 so as to cover switch 12 in the operative position of the fixing plate 26, by means of its upper shield portion 28, while any of the faces of the cutter 34 is adjusted. Thus the operator of the machine

is induced to move back the fixing plate 26 in its guide groove before operating switch 12.

The adjustment of my novel cutting apparatus is made as follows:

5 (a) Fixing the cutter faces:

At first the fixing plate 26 is pushed into its guiding groove and locked in the desired position by means of the lever 27. By slightly loosening the three locking screws 41 at the respective stop disc 17 or 18, being actually exposed to the pressure of stop pawl 19, it is possible to turn the stop disc 17 or 18, by operation of the respective worm wheel segment 24 or 25, through the companion worm 20 or 21. The movement resulting therefrom is transmitted through the stop pin 22 or 23 automatically conforming to the stop plates of the stop pawl 19, to the stop pawl 19, which in turn, being keyed to the cutter shaft 11, transmits this rotary motion to the cutter which is keyed to the opposite shaft end. Thus it is easily possible to adjust or fix the vertical height of the cutter faces with an accuracy of 0.02 to 0.01 mm. By the subsequent tightening of the three locking screws 41 which had been loosened before, a double aim is attained, i. e., the jamming of the real stop disc 17 or 18, and the forcing of the conical stop pin 22 or 23, into the conical opening of the stop disc. One cutter edge is now accurately fixed. Before fixing the second cutter edge, it is necessary to release the fixing plate 26 and to move it in the direction towards the casing 29 until a free rotary motion of the cutter 34 is possible. Only now the switch 12 is exposed by the shield 28 and can be swung by hand from its normal operative position I to its position II. The electric circuit closed by one of the limit switches 13 or 14 is now switched from one of the coils, 1 or 2, to the other coil 2 or 1. The respective coil now attracts its iron core 3 or 4, whose axial motion is transmitted, through its lower toothed rack portion 32 or 33, and the intermediate toothed wheel 5 meshing therewith, to the toothed wheel 6 which is keyed on the cutter shaft 11, thus producing a corresponding rotary motion of the cutter. However, since the stop pawl 19 is keyed to the opposite end of the cutter shaft 11, this rotary motion is limited by engagement of pawl 19 with the corresponding stop pin 22 or 23.

50 Now the whole procedure described above with respect to the first cutter edge is repeated in fixing the second cutter edge. Before putting the table planing machine into operation, it is necessary to remove the fixing plate 26 to fixedly tighten the three locking screws 41 of each stop disc and afterwards to turn switch 12 to its normal position I.

The machine is now ready for operation.

In operation, the coils 1 or 2, are energized with each reversal of the stroke of the table, through the limit switch 13 or 14, by a current impulse, thereby causing a swinging movement of the cutter for bringing the respective cutter edge 7, or 8, or 9, or 10, into its operative position, as hereinbefore described. It will be understood that the cutting pressure is taken up by the stop discs 17 or 18, as described above, rather than by the toothed wheels 5, 6. On the other hand, the shocks produced on reversal of the stroke are absorbed or damped by the two compression springs 15 and 16 counteracting the attraction force of the coils 1 and 2.

75 It will be understood that it would also be possible to operate the cutter shaft by hydraulic means instead of by the solenoid magnets 1, 2, 3.

4. The constructional changes required in this case will be obvious for one skilled in the art and therefore will not require special illustration and description.

The advantages of my novel cutting apparatus are very considerable.

The increase of output of table planing machines attainable by my novel cutting apparatus will amount to about 30 to 45%, depending on the size of the machine, i. e. the larger the length of stroke, the more the apparatus will help to increase the production. Moreover the lateral planing zone can be better utilized. Since the cutter can be secured at both sides of the apparatus, a rigid guiding of the tool, i. e., the cutter, is ensured on the whole width between the standards on both sides. It is possible to use accurately ground profiling or figure forming tools which are more economical than the conventional tools. These profiling tools can be made on any middle-sized turning lathe and it is possible to use even very tough types of steel which are not easily malleable.

On the other hand, if desired, it would also be possible to use ordinary planing tools by means of a special tool holder which is adapted to be keyed to the cutter shaft 11 and to secure the ordinary planing tools.

Furthermore, the drive of the machine becomes simpler, since the conventional accelerated return stroke can be dispensed with.

It may be necessary to design the two main standards of the table planing machines in such a way that the cross rail has equal strength in both directions of motion of the table.

While the invention has been described in detail with respect to a now preferred example and embodiment of the invention it will be understood by those skilled in the art after understanding the invention, that various changes and modifications may be made without departing from the spirit and scope of the invention and it is intended, therefore, to cover all such changes and modifications in the appended claims.

Having thus described my invention, I claim as new and desire to secure by Letters Patent:

1. In a machine tool of the kind described, in combination with a cross bar and a tool slide which is slidably mounted thereon; means mounted on the slide for rotation about an axis parallel to said cross bar and including a cutting tool having two cutting edges directed to opposite sides, said means being provided with two stop faces parallel to said axis; two elements mounted on said slide for rotation about axes parallel to said first named axis, each of said elements being provided with a counter-stop face adapted to cooperate with one of said stop faces; locking means for arresting said element on the slide; and a drive operatively connected to the rotatably mounted means so as to cause alternate engagement of the stop faces with one or the other of said counter stop faces by rotation of the rotatable means, for holding one of the two cutting edges in its operative position.

2. In a machine tool of the kind described, in combination with a cross bar and a tool slide which is slidably mounted thereon, a shaft having a free end and being rotatably mounted on the tool slide; a cutting tool non-rotatably secured to this end and having two cutting edges directed to opposite directions of rotation in relation to the shaft; a stop non-rotatably secured to the shaft and having two stop faces parallel to the shaft; two counter-stops adjustably ar-

ranged in the path described by the stop faces of the stop on its rotation; holding means for the counter-stops, said holding means being arranged on the tool slide and designed so as to guide the counter-stops along the said path described by the stop faces of the stop; and a drive operatively connected with the shaft so as to cause alternate engagement of the stop faces of the stop with one of the said counter-stops, for holding one of the two cutting edges in its operative position.

3. In a machine tool of the kind described, in combination with a cross bar and a tool slide which is slidably mounted thereon, a casing fastened on the cross bar; a shaft rotatably mounted in the casing with its end protruding therefrom; a cutting tool non-rotatably secured on one of these ends and having two cutting edges facing in opposite directions of rotation with respect to the shaft; a stop non-rotatably secured to the opposite end of the shaft and having stop faces which are parallel to the shaft, two counter-stops adjustably arranged in the path described by the stop faces of the stop on its rotation; holding means for the counter-stops secured to one of the outer sides of the casing, said holding means being designed for guiding the counter-stops along the said path described by the stop faces of the stop; and a drive accommodated between the cutting tool and the stop in the casing and connected to the shaft, whereby through rotation of the shaft the stop faces of the stop can alternately be caused to engage one of the two counter-stops to keep one of the two cutting edges in its operative position.

4. In a machine tool of the kind described, in combination with a cross bar and a tool slide which is slidably mounted thereon, a casing fastened on the cross bar and having two opposite end faces, a shaft mounted for rotation in the casing and having ends of similar configuration protruding beyond the said end faces, a cutting tool having two cutting edges directed to opposite directions of rotation in relation to the shaft, a stop having stop faces which are parallel to the shaft, the cutting tool and the stop being designed for alternative attachment to either end of the shaft, a plate adapted for detachable fastening on any of the end faces of the casing, two counter-stops, each arranged on the plate for rotation about an axis parallel to the shaft and protruding into the path described by the stop faces of the stop with one rotation of the shaft, and a drive accommodated in the casing between the cutting tool and the stop and operatively connected with the shaft, for causing the stop faces of the stop, by rotation of the shaft, to engage alternately one of the two counter-stops and to keep one of the two cutting edges in its operative position.
